PACKING HOLDER FOR FRAGILE ARTICLES

Fred D. Gray and Ralph Farnham, Herkimer,
N. Y., assignors, by mesne assignments, to Pack-
ing Products Corporation, a corporation of
Delaware

Application February 10, 1930, Serial No. 427,116

12 Claims. (Cl. 217—26.5)

The present improvements relate, in general, to packing holders for fragile articles, such as eggs, fruits, and other globular articles, and are more particularly designed to provide a foldable holder or filler adapted for use as a container or within other cartons or containers.

A primary object, among others, is to provide a foldable carton or carton filler so formed and designed as to provide a plurality of individual article compartments or cells by a simple folding operation.

A further object of the improvements is to provide a durable and sturdy article holder possessing inherent cushioning characteristics and having means for cushioning and protecting the packed articles from all sides, as well as one having separating means for the articles, forming a part of the holder.

Another object is to provide a holder which has no flat portions and no flat bottom member, but has a novel type of base or bottom including a cushion and hinge means with which article-conforming depressions and projections of the holder walls conform or merge. The provision of a novel type of folding or hinge means, constitutes a further object of the invention. In the present embodiment, this novel folding means supplies the connection between the cushion means of the bottom of the cell and the upstanding article protecting walls or depressions whereby these elements cooperate to provide a compartment substantially conforming to the shape of the packed article so that such article is efficiently cushioned, protected, separated from its companion articles and prevented from movement or wabbling within the cell.

Other objects include the provision of protecting and strengthening means for portions of the holder. Further objects and advantages of the improvements will be apparent to those skilled in the art upon reference to the accompanying specification and drawings in which—

Fig. 1 is a plan view of the improved holder, in unfolded position;

Fig. 2 is a top plan view of the holder in folded position;

Fig. 3 is a section on line 3—3 of Fig. 1;

Fig. 4 is a section on line 4—4 of Fig. 2;

Fig. 5 is a longitudinal section, partly in elevation on line 5—5 of Fig. 4;

Fig. 6 is a side elevation looking in the direction of the arrow in Fig. 4;

Fig. 7 is a view similar to Fig. 4, but illustrating a modified form.

In the embodiments illustrated herein, the car-

ton or filler consists of a single sheet of material, all parts of which are preferably formed integral with the sheet in one operation. The sheet is preferably formed by the pulp sucking or felting process wherein floating fibres are drawn against a screen member, so that the carton or filler is created complete in one operation. Accordingly, the foraminous die or mold is so shaped that the pulp deposited thereon will assume the prescribed form and contour of the filler.

Referring to the drawings, the sheet 10 shown in flat or unfolded position in Fig. 1, is preferably formed in the above described manner. In the present embodiment, said sheet comprises a plurality of substantially parallel sections or wall portions 11 to 14. Each such wall portion includes a series of alternately disposed projections 15 and depressions 16 merging with one another and with the edges of the portions, so as to present a wall member of continuously curved or arched surfaces.

Referring to the projections 15, it is seen that they are of substantially pyramidal or prismatic form, the walls however being curved or cambered in all directions. Upon reference to the drawings, it is seen that these projections substantially traverse the wall portion of which they form an integral part. Likewise, while said projections protrude to their greatest extent substantially medially of the wall portion, at which region the outermost portions are narrow in the nature of a ridge, they are broader adjacent the edges of the wall portions, e. g., at 17 and 18, at which points they likewise curve slightly in all directions.

The depressions 16 are cup-like recesses integral with the sheet and disposed between adjacent projections. In the present embodiment these depressions are concave and are substantially oval shaped. While these depressions extend in a direction opposite to that of the projections, it is notable that the curved walls of the depressions merge with their flanking projections, so that a half-ovoid cavity results.

It is to be noted that the depressions and projections of one wall member are disposed opposite to those of the adjacent wall member so that similar members on adjacent wall members are complementary. Such adjacent wall members, e. g., 11 and 12 are connected by an integral fold line or hinge 19 which unites complementary portions 18, which are between the depressions, as at 20. In addition to hinge sections 20, an annular or curved fold line or hinge 21 is provided be-

100

95

100

105

110

tween complementary depressions 16. Said hinge 21, as illustrated, units with hinge sections 20, and at the same time provides a connection between opposed depressions 16 and a cushion member 22.

In the present embodiment, said cushion members 22 are in the form of annular supports or seats. Upon reference to Figs. 3 to 6, it is seen that these cushion supports are of substantially frusto-conical form having arched or inclined upstanding outer walls, protruding to form a ring, whence they recede in an opposite direction forming an inner cup or crater-like surface. While this form of article support is preferable, it is understood that such member may take other forms.

It is notable that the lower annular limits of this cushion member 22 merge with the annular hinge 21, while the lower extremities of the depressions 16 likewise merge with said hinge, so that the latter directly connects the depressions and annular cushion member without any intermediate flat or horizontal portions. Attention is also invited to the fact that the lower extremities of the depressions curve and converge toward the members 22 and the hinges 21. This feature is exemplified at 23, Fig. 1.

While wall portions 11 and 12 and portions 13 and 14 are thus connected, it is seen that portions 12 and 13 are united by an integrally formed hinge connection 24.

Upon reference to Figs. 2 and 4, the sheet 10 may be seen in folded relation to form an article holder. By folding the sheet downwardly along connecting portion 24 and again in an opposite direction along hinges 20 and 21, it is seen that an article holder results, as illustrated in section in Fig. 4. In this manner, complementary wall portions 11, 12 and 13, 14 are disposed in upstanding relation with projections 15 and depressions 16 of each, brought into juxtaposition, the former substantially meeting at their lower limits. Accordingly, a plurality of individual cells or compartments are formed with a cushion base 22 therefor. The curved and merging walls of the projections and depressions provide a rounded or ovoid shaped cell which conform to the contour of an egg which is adapted to rest on the cushion seat 22. The contraction or convergence of the lower limits of the depressions, merging with the annular hinge and in immediate proximity to the annular cushion 22 insures that the walls of the completed compartment will conform to the contour of the egg. It is understood that the shape of the article-conforming depressions 16 may be varied to suit the contour of other articles.

In examining the completed holder shown in folded relation in Fig. 4, it is seen that the rings or annular cushions 22 serve as supports for the packed articles, functioning to hold them erect. Furthermore, the cup-like depressions and projections may cooperate to maintain the articles upright. In packed condition the articles are enclosed and supported by the holder, are completely separated one from another and are efficiently cushioned and protected throughout due to the form and texture of the holder.

Upon reference to Fig. 6 the novel spring or cushion action of the annular seats is illustrated. In folding the holder from the unfolded position (Fig. 3) to the folded position (Fig. 4) a transposition of parts occurs due to the inherent leverage of the holder attendant the annular hinges, depressions, etc. In the unfolded position of Fig. 3, the annular rings 22 and hinges 21 are

substantially on the horizontal dotted line while the intermediate hinge means 20 are slightly above such dotted line. In folding the holder to the position of Fig. 4, the inherent leverage causes the aforementioned parts to change places, so to speak, so that the hinge means 20 are brought down to the horizontal while the annular hinges 21 and cushions 22 are slightly raised above the horizontal. While this effect is evident in Fig. 4, it is seen more clearly in Fig. 6. This result is probably attributable to the provision of the annular hinge, as well as to the fact that the seats 22, depressions 16 and projections 15 merge therewith. It is seen therefore, that the hinge means 20 serve as the base of the holder, while the annular cushions 22 have added resilience due to the freedom of movement up and down from the raised position (Fig. 6) to the plane of the member 20. By affording this slight movement it is apparent that added cushioning effect is provided for each article and compartment. Should it be found unnecessary or undesirable to provide this auxiliary resilience, the improvements contemplate such an arrangement so that the annular seats and hinges are disposed in the same horizontal plane.

The present invention is accordingly in the nature of an improvement on the copending application of Morris Koppelman, Serial No. 384,591, filed August 9, 1929. In addition to advantages already noted, the present improvements provide an individual cushion seat for the packed articles without sacrificing the advantages of the Koppelman structure. By providing this ring in the bottom of each compartment with a fold line 110 surrounding same, added flexibility and adjustability is effected without interfering with the strong yet resilient support of the article by the ring. Furthermore, the size of the space at the bottom of the pocket or cell is reduced so that the articles are held snugly. In adopting a single longitudinally extending hinge at the bottom of the cell row instead of two or more, an efficient embodiment results, having the advantages of a cushion seat as well as of a cupped or inclined wall structure. Furthermore, the novel combination of the annular seat and single hinge serves to keep the holder in position in a carton when it is employed as a filler, this feature being of marked advantage when the filler is only partially filled.

When the articles are packed in the holder, it is important that they be protected from shocks from above, and for this reason the central hinge connection 24 protrudes above the upper level of the eggs, as well as slightly above the walls of the surrounding carton. However, such provision does not entirely insure against certain shocks or pressure, which may cause the connection to spread or collapse with the attendant loss of the protecting function. In the present improvements, this hinge connection is made unusually rigid and protective by the provision of one or more ribs 25 in line with each compartment. In addition to this refinement of construction, a combined strengthening rib and cushion 26 is provided in association with each depression. As illustrated this member is disposed in part of each depression 16 and extends therebeyond and into the hinge connection 24. Accordingly, said connection as well as the upper edges of the side walls are additionally braced against shocks, since the members 26 not only prevent crushing of the upstanding connections and edges but also assist in dissipating and re-

sisting pressure experienced from above, through the arched or curved walls of the depressions 16 and projections 15 of the upstanding side walls.

The provision of these cushion ribs 26 therefore causes the upstanding walls to resist pressure experienced by the hinge connection, making the latter more rigid, and also prevents the possibility of a crease or weakened area being set up at the region where the walls 12, 13 and hinge connection 24 meet.

An additional function of these ribs 26 resides in the fact that they protrude beyond the surface of the depressions 16 and therefore beyond the surface of the egg or other packed article so as to provide a shock resisting cushion on each side of the individual cell or pockets. Furthermore, as seen in Fig. 4, these members 26, on the inner upstanding walls 12 and 13, serve as buffers or spacers, and therefore prevent articles and even the article compartments of one cell row from contacting those of the adjacent cell row. It is therefore apparent that the curved depressions 16 of wall members 12 and 13, are spaced even though the ribs 26 are contacting and said wall members are in upright article holding position. While the members 25 and 26 represent a feature of marked advantage, it is apparent that they may be omitted from the holder, if desired.

The holder of the modified form, illustrated in Fig. 7, is substantially the same as that of the form first described, except that the projections 15a protrude to a greater extent so that complementary projections contact, so as to provide a complete barrier or separator between the cells. Besides performing this function, the contacting projections 15a serve as cushions or spacers for cushioning and resisting shocks laterally of the holder.

Various other modifications, within the scope of the improvements, may be made without departing from the purview of the invention.

We claim:

1. A holder for fragile articles comprising side wall members each having a row of cup-shaped depressions, a plurality of spaced fold lines aligned end toward end, and spaced longitudinally of the rows of depressions providing spaced hinges for portions between depressions, article seats between the ends of said fold lines, said seats being associated with said depressions, the lower extremities of said depressions being in proximity to said seats.

2. In a foldable holder, an annular cushion member, curved hinge means curving about the periphery thereof and a wall member having an article receiving depression, the lower surface of said depression being substantially coincident with said hinge means.

3. In a foldable holder, an annular cushion member, annular hinge means curving about and surrounding same, and an upstanding wall member connected to said cushion member by a portion of said hinge means.

4. A foldable holder for fragile articles comprising a plurality of upstanding wall members, substantially horizontally disposed cushion means therebetween, and a plurality of curved hinge means connecting said walls and curving about said cushion means.

5. A holder for fragile articles comprising side wall members and a plurality of spaced annular

article seats, said wall members having an article conforming depression associated with each seat, the lower extremities of said depressions being respectively inclined toward the peripheries of the seats, and hinge means consisting of curved and straight portions connecting said wall members to each other and to said seats.

6. A foldable holder for fragile articles formed of a sheet of material folded to form a trough having upstanding walls, a series of article seats and fold lines, a plurality of said seats and fold lines being aligned endwise and defining the bottom of said trough, said seats and fold lines being alternately arranged along the length of the trough, said walls being hinged to each other by said fold lines.

7. A foldable holder for fragile articles formed of a sheet of material folded to form a trough having upstanding walls, a series of article seats and fold lines, a plurality of said seats and fold lines being aligned endwise and defining the bottom of said trough, said seats and fold lines being alternately arranged along the length of the trough, said walls being hinged to each other by said fold lines, and further hinge means connecting each wall to each seat.

8. A foldable holder for fragile articles formed of a sheet of material folded to provide a trough having upstanding walls, said walls having a common connection at their base comprising a series of fold lines aligned endwise in spaced relation, and article seats disposed between said walls and between the ends of said fold lines.

9. A foldable holder for fragile articles formed of a sheet of material folded to provide a trough having upstanding walls, said walls having a common connection at their base comprising a series of fold lines aligned endwise in spaced relation, and annular seats disposed between said walls and between the ends of said fold lines.

10. A foldable holder for fragile articles formed of a sheet of material folded to provide a trough having upstanding walls, said walls having a common connection at their base comprising a series of fold lines aligned endwise in spaced relation, annular seats disposed between said walls and between the ends of said fold lines, and said walls being hinged to said annular seats.

11. A foldable holder for fragile articles formed of a sheet of material folded to provide a trough having upstanding walls, said walls having a common connection at their base comprising a series of fold lines aligned endwise in spaced relation, and article seats disposed between said walls and between the ends of said fold lines, and article conforming depressions in said walls opposite said seats.

12. A foldable holder for fragile articles formed of a sheet of material folded to provide a trough having upstanding walls, said walls having a common connection at their base comprising a series of fold lines aligned endwise in spaced relation, and article seats above the plane of said fold lines and between the ends of said fold lines for holding the articles out of contact with the support on which the holder rests.
